UNITED STATES PATENT OFFICE.

GEORGE B. SNOW, OF BUFFALO, NEW YORK.

VULCANIZER.

SPECIFICATION forming part of Letters Patent No. 357,639, dated February 15, 1887.

Application filed August 27, 1886. Serial No. 212,015. (No model.)

To all whom it may concern:

Be it known that I, GEORGE B. SNOW, of the city of Buffalo, in the county of Erie and State of New York, have invented a new and Improved 5 Vulcanizer, of which the following is a specification, reference being had to the accompanying drawing, which is a vertical central section of the vulcanizer.

This invention relates to that class of vulcanizers in which the article to be vulcanized is placed in a chamber, which during the process of vulcanization is filled with steam from a steam-boiler connected therewith. Its object is the arrangement of the parts in such relation 15 to one another as to insure sufficient heat being imparted to the vulcanizing-chamber directly to insure its constant dryness, while its temperature cannot, on the other hand, be but slightly raised above that of the steam-boiler which 20 supplies it with steam.

It consists in placing the vulcanizing-chamber inside the steam-chamber or boiler, making the latter an annulus, so that the bottom of the vulcanizing-chamber and the bottom of the 25 boiler shall form one continuous surface externally and each shall receive its part of the heat from one flame, as will hereinafter be more fully described.

Referring to the drawing, A represents the 30 vulcanizing-chamber and its walls, with an external annular flange, a, near the top. The chamber is closed by the lid B, which is packed so as to be steam-tight when closed. The fastening of the lid B is shown as a simple screw; but 35 it may be secured by bolts and nuts, or in any other way preferred. If the bottom of the chamber A is flat and of equal diameter with the chamber, it will expose too much surface to the flame and will become overheated. I therefore 40 make it in the shape of a truncated cone, C, and I am thus enabled to convey just that proportion of heat to the vulcanizing-chamber which will insure its dryness without raising its temperature more than a few degrees above 45 that of the surrounding steam-chamber.

The shell D is shown encircling the chamber A, its upper edge fitting the flange a. A short boss, c, on the bottom of the chamber A fits a hole in the bottom of the shell D, so that there 50 will be joints between the two parts at a' and c'. These joints should be turned to a close fit and brazed or soldered. The vulcanizer-body will

then be substantially one piece, as the two parts will thereafter be inseparable.

Communication between the two chambers 55 is made by means of the valve V, and steam is thereby admitted to the chamber A when it is desired to vulcanize any article contained therein.

A steam-gage, S, is shown as attached to the flange a for the purpose of indicating the steam-pressure in the boiler-space d. The usual thermometer may be used instead; but the steam-gage is to be preferred. A blow-off cock, b, surrounds the cover B. A safety-valve and suitable means for supplying water occasionally to 60 the boiler are necessary, but are not shown, as their application is familiar to all mechanics.

The vulcanizer is supported by a jacket, J, at a suitable height to allow of the introduction of a lamp or gas-burner beneath it.

In using this vulcanizer, the outer chamber or boiler-space, d, is half-filled with water, and closed so as to be steam-tight. The valve V is closed, and a lamp or gas-burner is placed beneath the vulcanizer, which is thereby heated 75 until the steam-gage indicates the proper steam-pressure, which will be from sixty to one hundred pounds to the inch. The flask containing the rubber is placed in the chamber A, which is closed by screwing on the cover B. 80 The valve V is then opened and the chamber A filled with steam. Any condensation from the sides of the flask or the cover B drops to the bottom C of the chamber A, which, receiving heat directly from the flame with the boiler, 85 will re-evaporate the condensation. The chamber A will therefore be filled with dry steam, and the rubber, when properly vulcanized therein, will be strong, elastic, and of good color. It will not be overheated, for as soon as 90 the space c is sensibly higher in temperature than the surrounding parts conduction sets in, and the heat is carried off to and absorbed by the surrounding water W in the boiler-space d.

The time required to properly vulcanize 95 rubber in this vulcanizer will be from one to three hours, according to its quality and the temperature and pressure of the steam. At the expiration of the time the valve V is closed and the steam is let off from the vulcanizing-chamber by means of the blow-off cock b and the cover B removed. The flask can then be taken from the vulcanizer and other ones put in without allowing the vulcanizer to cool, the cover

B being immediately replaced and steam turned on by means of the valve V, when the vulcanizing process will be immediately resumed.

I claim as my invention—

5 1. The combination of a vulcanizing-chamber and an external concentric steam-generating chamber having one continuous surface at the bottom, so that each chamber will receive its quota of heat from one common flame, substantially as described.

10 2. The combination of a vulcanizing-chamber and an enveloping steam-chamber, the

bottom of the vulcanizing-chamber projecting through the bottom of the steam-chamber and forming one continuous external surface with it, substantially as described.

15 3. The vulcanizing-chamber A, with its conical bottom C, forming part of the bottom of the steam-generating vessel D, substantially as described.

GEORGE B. SNOW.
